DESIGN FOR A DRESS

Esther Alper, New York, N. Y.

Application January 21, 1937, Serial No. 67,173

Term of patent 3½ years

To all whom it may concern:

Be it known that I, Esther Alper, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view of a dress as shown in Fig. 1. The characteristic feature of my design resides in the scarf-like appearance of the added piece of material on the back of the dress, which material is draped to form the collar as shown.

I claim:

The ornamental design for a dress substantially as shown and described.

ESTHER ALPER.
